UNITED STATES PATENT OFFICE.

CHARLES A. HAWLEY, OF OAKLAND, CALIFORNIA, ASSIGNOR TO THE AUTOMATIK CHEST COMPANY, COMPOSED OF FREDERICK W. KEWELL AND CHARLES A. HAWLEY, OF OAKLAND, CALIFORNIA.

DESIGN FOR AN ODORIZER HOLDER.

Application filed September 19, 1925. Serial No. 14,833. Term of patent 3½ years.

To all whom it may concern:

Be it known that I, CHARLES A. HAWLEY, a citizen of the United States, and a resident of the city of Oakland, county of Alameda, State of California, have invented a new, original, and ornamental Design for an Odorizer Holder, of which the following is a specification, reference being had to the accompanying drawing, forming part thereof.

The drawing is a perspective view of the holder illustrating my design.

I claim:

The ornamental design for an odorizer holder substantially as shown.

CHARLES A. HAWLEY.
